PRINTING APPARATUS

George W. Booth, Baltimore, Md., assignor to
Crown Cork & Seal Company, Inc., Baltimore,
Md., a corporation of New York

Original application August 28, 1935, Serial No.
38,307. Divided and this application May 9,
1936, Serial No. 78,925

14 Claims. (Cl. 101—35)

The present invention relates to apparatus particularly designed for printing or otherwise imposing data or decorative matter on articles such as container closures. A general object of 5 the invention is to provide means whereby the articles may be impressed upon with precision, and a particular object is to provide means whereby articles having surfaces in different planes may have matter accurately imposed on 10 the different surfaces.

The apparatus in the embodiments hereafter to be described is particularly designed to handle closure discs having central and marginal portions in different planes, closures of this type 15 being disclosed in my Patent No. 1,956,217, issued April 24, 1934.

In the accompanying drawings, which illustrate practical embodiments of the invention by way of example:

20 Figure 1 is a vertical section through a pair of printing rolls, associated inking rollers, and a platen.

Figure 2 is a section substantially on the line 2—2 of Figure 1.

25 Figure 3 is a section substantially on the line 3—3 of Figure 1.

Figure 4 is an enlarged vertical section taken at the bottom of the right hand roll of Figure 1.

Figure 5 is a sectional view taken at the bottom 30 of the left hand roll of Figure 1.

Figure 6 is a partial elevation partly in section of a modified form of printing roll.

Figure 7 is a section substantially on the line 7—7 of Figure 6.

35 Figure 8 is a plan view of a printing band appearing in elevation in Figure 6.

Figure 9 is an axial section of a further modified form of printing roll.

Figure 10 is an elevation partly in section of the 40 devices of Figure 9 as seen from the left of that figure.

Figure 11 is a plan view of a portion of the printing roll of Figure 9, partly in section, on line 11—11 of that figure, and

45 Figure 12 is a partial axial section of another modified form of printing roll.

The apparatus as a whole, as disclosed in my copending application Serial No. 38,307, filed August 28, 1935, of which this is a division, comprises means for feeding the discs to be printed from stacks and under the printing rolls. For the sake of conciseness, the stack feeding mechanism has not been shown in the present application, since merely the printing appliances are 55 here involved.

Referring first to Figures 1 to 5 of the drawings, reference numeral 20 designates one of the printing rolls and 21 the other, groups of inking rollers 22 and 23 being associated with the respective printing rolls. The main machine comprises a frame which includes an upright rear wall portion 24 and rolls 20 and 21 are respectively mounted on shafts 25 and 26 which are journaled in bushings as at 27, Figure 2, secured in suitable openings in the wall 24. Each shaft has fixed thereto a gear as at 28, both of these gears being of equal size and both engaging a drive gear so as to be driven at the same speed and in the same direction.

A platen comprising portions 29 and 30 is supported beneath the respective rolls on eccentrics 31, 32, 33 and 34, which have end portions journaled in the main frame. By means of mechanism described in my original application, the pairs of eccentrics 31, 32 and 33, 34 are rockable so as to adjust the platen portions 29 and 30 independently and translationally in a vertical direction. The platen portions are provided with channels as at 35, Figures 3 to 5, which receive an endless feed chain 36 which has upstanding fingers 37 adapted to abut and propel along the guideway 38, closure discs, as at 39. As may be seen from Figures 1 and 3 to 5, each closure disc comprises flat central and marginal portions of which the central portion is in a plane above the 30 marginal portion. The discs are of circular form so that their marginal portions are annular and their central relatively offset portions circular.

As herein contemplated, roll 20 is designed to print on the depressed annular portions of the 35 discs and roll 21 on the raised central portions. Except for the printing pads used, the two rolls are identical and the following discussion directed to roll 21 will be understood to apply also to roll 20.

Roll 21 comprises a central core member 40, an intermediate ring portion 41, and an outer ring portion 42. The core 40 is keyed on shaft 26 and held against outward axial movement by a washer 43 secured to the end of the shaft. At 45 its outer end the core has a flange 44 expanded at diametrically opposite points to provide lugs 45 and 46 which lie against the outer face of ring portion 41. Lug 46 has a transverse slot 47 through which is passed the shank of the screw 50 50 threaded in a tapped hole in ring 41. Lug 45 projects between a pair of split lugs 49 and 50 projecting outwardly from ring 41, these lugs carrying abutment screws 51 and 52 whose adjacent ends bear against lug 45. Ring 48 may be 55

turned relative to core 40 upon loosening screw 48 and adjusting screws 51 and 52. In this manner the required angular adjustment of the ring and core may be effected, screws 51 and 52 locked in 5 abutment with lug 45 by means of the locking screws 53 and 54, and screw 47 tightened to hold ring 41 against lug 46.

At its rear edge ring 41 has an annular shoulder 55 abutted by ring 42, the two rings being 10 keyed together as indicated in Figure 3. In radial grooves 56 and 57 formed in the bottoms of channels 58 and 59 on the front face of ring 41 are disposed a pair of lugs 60 and 61, these lugs being secured to ring 41 by means of screws 62 and 63. 15 The outer ends of lugs 60 and 61 overlap the inner margin of ring 42 to secure the latter against shoulder 55.

The side faces of ring 42 are provided with annular grooves 64 and 65. Disposed about the 20 periphery of ring 42 in equally spaced relation are a series of printing pads 66 which may be conveniently formed of rubber although any other suitable material may be used. Each pad 66 has a printing area for engagement with the 25 central portions of the discs and each is secured as by an adhesive to an arcuate base plate 67 whose curvature is that of ring 42. The lateral edges of each base plate 67 are engaged by the beveled ends of substantially U-shaped clamps 30 or clips 68 and 69. The legs of each clamp are respectively engaged in one of the grooves 64 and 65 and against an edge of a plate 67, the bridge portions of the clamps being ordinarily somewhat spaced from the sides of the ring as 35 indicated in Figure 3. The clamps are secured to ring 42 by means of screws 70 and 71. It will be evident that upon loosening the screws the plate may be slid circumferentially of ring 42 and may also be adjusted transversely thereof or in 40 the axial direction of the roll by proper adjustment of the screws. In Figure 3, for example, the base plate 67 is shown as being adjusted slightly to the right relative to ring 42 for the purpose of securing proper register. If necessary, shims may be interposed between the base plates and ring 42 to insure uniform printing of 45 the pads.

Referring particularly to Figure 5, the base plate 72, secured to roll 20, is shown as having 50 affixed thereto a printing pad 73 having an annular printing face 74 of a size to engage and print the annular marginal portions of the closures. The central portion of pad 73 is spaced above the upwardly offset portion of the closure 55 so as to prevent smearing of the printing previously effected by a pad 66.

The printing pads are spaced apart on their respective rolls at intervals corresponding exactly to the spacing of the closures as fed under the 60 rollers and over the platen by fingers 37, and the relative adjustment of the chain and rolls is such as to bring successive discs into exact printing registry with successive pads. The rolls are driven so that the printing surfaces of the pads 65 move at exactly the same speed as the chain. Clearance is provided between the pads for the upper extremities of the feeding fingers 37.

As disclosed in my original application, the 70 drive trains for the rolls and chain are interconnected so that proper coordination is secured. It will be understood that as chain 36 moves to the left, Figure 1, a disc 39 is brought into engagement with a printing pad 66, the pad rolling on the high portion of the disc and printing 75 thereon. As the travel of the disc is continued

it comes under roll 20 and the annular portion 74 of a pad 73 rolls on the low marginal portion of the disc to apply the desired printing. The path of the printing surface of pads 66 is elevated with respect to the platen as compared 5 to the path of the printing surface of the pads 73. The inking rollers 22 and 23 are, of course, positioned so as to engage the printing surfaces of the associated printing members.

The closures may be simply metal plates or 10 may be laminated construction. Where the printing surfaces are metal, a drying oven is ordinarily required but with the printing surfaces of paper, for example, which will absorb the ink, the oven can be dispensed with.

In the described machine, two rolls are provided for printing on different surfaces of a closure or the like. If it were desired to print on only one surface, or if the disclosure were uniplanar, one roll could, of course, be dispensed 20 with. The principal purpose of providing the two rolls is to avoid the difficulty of inking a printing pad having printing surfaces at different levels. However, with the single roll a printing roller may be provided for inking the outer level 25 of a plural level pad and a further roller for inking the lower level. The latter roller would be provided with localized inking pads moved in timed relation with the printing roller so that successive inking pads would cooperate with successive printing pads. In the present case, if pads 66 and 73 were combined into a single pad, a plain cylindrical inking roller could be provided for the outer annular printing portion 74 and a cylindrical roller with raised inking pads for co- 30 operation with the relatively lower surfaces 66. 35

The printing rolls may be designed to carry a flexible band on which the pads are properly spaced and fixed.

In Figures 6 and 7, a roll 15 is shown as carrying 40 a split band 76 on which are affixed at proper intervals the printing pads 77, the band and pad being shown in plan in Figure 8. At its ends the band has affixed thereto wedge-shaped blocks 78 and 79, these being received in a groove 80 extending transversely of the roller periphery. A transverse rib 81 in groove 80 and integral with the roll, lies between blocks 78 and 79. A U-shaped locking member 82 having legs 83 and 84 with wedge faces for engagement with blocks 78 45 and 79, is pulled into engagement with the latter by means of a screw 85, threaded in the end of rib 81, for the purpose of tensioning the band. Legs 83 and 84 are undercut, as shown, in Figure 50 6, so that the ends of the band are held down. The ends of blocks 78 and 79 opposite screw 85 55 abut an annular shoulder on the roll to prevent their transverse displacement under the action of member 11 and the roll, as shown, may have a shallow peripheral channel providing shoulders 60 which accurately position the band. The advantage of this arrangement is that the pads may be accurately placed on the band and the whole group quickly applied to the roll in a single operation. In the embodiment first described, if different printing members are to be applied, this is ordinarily done by removing the pads from 65 ring 42 and replacing with other pads. Of course, a ring 42 could be removed without disturbing the positioning of the pads thereon and another 70 ring with different pads applied. However, this would be a rather lengthy operation as compared to the removal and reapplication of bands 76.

In Figures 9 to 11, I have shown means for moving an inner printing pad relative to an outer 75

pad so that the two may be at different levels for printing but at the same level for inking; this disposition, of course, requiring the provision of only a single roll. In the figures mentioned, the 5 ring 86 is provided in its side toward wall 28 with an annular groove 87. Peripherally the roll is provided with a series of circular radial recesses 88 having central cylindrical radial bosses 89 therein. Cup-shaped plungers 90 are positioned 10 in recesses 88 and as shown in Figure 11, have flanges 91 provided with radial projections as at 92 and 93 mating with similarly shaped axially extending grooves in the walls of the recesses to prevent turning of the members 90. On their 15 outer circular faces members 90 carry printing pads 94 which are radially movable in openings of printing pads 95 and the base plates 96 to which the pads 95 are affixed. The base plates are secured to the roll by means of screws 97. Interposed between plates 96 and the flanges 91 are compression springs 98 which tend to move members 90 inwardly. Each member 90 has secured thereto a cylindrical stem 99 slidable in a radial bore in a boss 89. In order that the members 90 20 may reciprocate freely with dash-pot effect, vent openings 100 and 101 are provided for the recesses. Secured to wall 24 and projecting within recess 87 are upper and lower substantially semi-circular cam members 102 and 103, the cam members 25 having flanges provided with vertically elongated slots 104 and 105 through which pass screws 106 and 107. The cams thus have a range of vertical adjustment. Cam 102 is formed on a somewhat greater radius than cam 103 and has 30 rounded end flanges overlying the ends of the latter in the manner shown in Figure 10, to provide a smooth peripheral track. The inner ends of stems 99 bear against cams 102 and 103 by reason of the action of springs 98. When any 35 stem is on cam 102 its associated pad 94 is projected outwardly to the level of the printing portion of pad 95 so that, the two parts being flush, they may be simultaneously inked by means of a plain cylindrical roller. When a stem 99 is on cam 103, its associated pad 94 is retracted by the spring 98 to the position shown in Figure 9 so as to print properly on the raised surface of the disc while the other pad is printing the disc margin. 40 The curve of cam 103 should, of course, be such that one pad will remain in the same relation to the outer pad throughout the printing operation. Thus the cam surface should be concentric with the roll axis. However, slight adjustment of cam 45 103 from a strictly concentric position may be made without unduly affecting the operation of the apparatus.

In Figure 12, the roll 108 is provided with equally spaced bores, as at 109. In each bore 109 is slidable a cup-shaped plunger 110 which carries a printing pad 111, this being movable within the outer printing pad 112. Plunger 110 is pressed outwardly by means of a compression spring 113, movement of the plunger being limited by means 60 of screws 114 and 115 passed through the walls of bore 109 and engaged in axially extending ended recesses 116 and 117 in the plunger. A vent duct is shown at 118.

Spring 113 normally holds the printing surface 70 of pad 111 flush with the printing surface of pad 112 for inking, the pad 111 being unable to move outwardly past the flush relation due to the limiting effect of screws 114 and 115. During the printing operation, however, the raised portion of 75 the closure pushes the pad 111 inwardly to the

position shown so that both levels of the cap are simultaneously printed.

It will be understood that the specific disclosures herein may be departed from without departure from the scope of the invention. Variations are possible in the form and arrangement of parts, and accordingly I do not limit myself except as in the following claims. 5

I claim:—

1. Apparatus for printing closure discs of the 10 type having high and low substantially flat portions, said apparatus comprising rotary means, a pair of printing members carried by said rotary means, and a rectilinearly extending platen for supporting the discs to be printed, one of said 15 printing members having a path elevated with respect to the platen as compared to the path of the other so that the first is adapted to print on the high portions of the discs and the other is adapted to print on the low portions of the discs. 20

2. Apparatus for printing closure discs of the 25 type having high and low substantially flat portions, said apparatus comprising rotary means, a pair of printing members carried by said rotary means, and a rectilinearly extending platen for 25 supporting the discs to be printed, one of said printing members having a path elevated with respect to the platen as compared to the path of the other so that the first is adapted to print on the high portions of the discs and the other 30 is adapted to print on the low portions of the discs, the printing action of said members being successive.

3. Apparatus for printing closure discs of the 35 type having high and low substantially flat portions, said apparatus comprising rotary means, a pair of printing members carried by said rotary means, and a rectilinearly extending platen for supporting the discs to be printed, one of said 40 printing members having a path elevated with respect to the platen as compared to the path of the other so that the first is adapted to print on the high portions of the discs and the other is adapted to print on the low portions of the discs, said rotary means comprising a pair of rolls, one 45 of the rolls carrying one of the printing members and the other roll carrying the other printing member, the printing members acting successively.

4. Apparatus for printing closure discs of the 50 type having high and low portions, said apparatus comprising rotary means, a pair of printing members carried by said rotary means, and a platen for supporting the discs to be printed, one of said 55 printing members having a path elevated with respect to the platen as compared to the path of the other so that the first is adapted to print on the high portions of the discs and the other is adapted to print on the low portions of the discs, the printing action of said members being substantially simultaneous. 60

5. Apparatus for printing closure discs of the 65 type having high and low portions, said apparatus comprising rotary means, a pair of printing members carried by said rotary means, and a platen for supporting the discs to be printed, one of said 70 printing members having a path elevated with respect to the platen as compared to the path of the other so that the first is adapted to print on the high portions of the discs and the other is adapted to print on the low portions of the discs, one of said printing members being surrounded by the other.

6. Apparatus for printing closure discs of the 75 type having high and low portions, said appara-

tus comprising rotary means, a pair of printing members carried by said rotary means, and a platen for supporting the discs to be printed, one of said printing members having a path elevated 5 with respect to the platen as compared to the path of the other so that the first is adapted to print on the high portions of the discs and the other is adapted to print on the low portions of the discs, one of said members being radially 10 movable relative to the other.

7. Apparatus for printing closure discs of the type having high and low portions, said apparatus comprising rotary means, a pair of printing members carried by said rotary means, a platen 15 for supporting the discs to be printed, one of said printing members having a path elevated with respect to the platen as compared to the path of the other so that the first is adapted to print on the high portions of the discs and the 20 other is adapted to print on the low portions of the discs, one of said members being radially movable relative to the other, and means for projecting the movable member from a relatively retracted printing position to an inking position 25 wherein it is substantially flush with the other member.

8. Apparatus for printing closure discs of the type having high and low portions, said apparatus comprising rotary means, a pair of printing 30 members carried by said rotary means, a platen for supporting the discs to be printed, one of said printing members having a path elevated with respect to the platen as compared to the path of the other so that the first is adapted to print 35 on the high portions of the discs and the other is adapted to print on the low portions of the discs, one of said members being radially movable relative to the other, means for projecting the movable member from a relatively retracted printing position to an inking position wherein 40 it is substantially flush with the other member, and means for retracting said movable member.

9. Apparatus according to claim 7 wherein the projecting means is constituted by a spring and wherein the movable printing member is retracted as a result of engagement with the high portions of the discs.

10. Apparatus according to claim 7 wherein the projecting means is constituted by a cam.

11. Apparatus according to claim 8 wherein the projecting and retracting means are constituted by cams.

12. Apparatus for printing closure discs of the type having high and low portions, said apparatus comprising rotary means, a pair of printing members carried by said rotary means, a platen for supporting the discs to be printed, one 15 of said printing members having a path elevated with respect to the platen as compared to the path of the other so that the first is adapted to print on the high portions of the discs and the other is adapted to print on the low portions of 20 the discs, one of said members being radially movable relative to the other, and means for moving the movable member from an inking position wherein it is substantially flush with the other member to a relatively retracted printing 25 position.

13. Apparatus according to claim 3 wherein the platen comprises separate portions respectively cooperable with the rolls, the platen portions being adjustable independently of each 30 other relative to their associated rolls.

14. Printing apparatus comprising a roll, printing pads having base plates curved as the roll periphery and spaced about the latter, and U-shaped clamps secured by screws to the sides of 35 the roll, one leg of each clamp engaging the side of the roll and the other leg engaging a side edge of a base plate, the arrangement being such that by adjusting the screws of opposite clamps the associated plate and pad may be adjusted 40 axially of the roll.

GEORGE W. BOOTH.
